PRICKING MACHINES

John Edwin Cannell, Sheffield, England, assignor to
Unilever Limited, Port Sunlight, England
Filed Feb. 12, 1958, Ser. No. 714,834
Claims priority, application Great Britain Feb. 18, 1957
17 Claims. (Cl. 146—56)

This invention relates to pricking machines and in particular to machines for pricking small regularly sized articles such as pulses.

It has been found advantageous to rupture the skins of pulses such as peas or broad beans before drying them. Pulses which have been so treated require less time to prepare for consumption.

It is an object of the present invention to provide a machine for pricking regularly sized articles such as pulses, and in particular a machine for pricking peas for the above purpose. It is a further object of the present invention to provide a process for pricking peas.

The present invention provides a pricking machine comprising a pin drum and a pocket drum mounted for rotation about their respective axes, the curved surface of the pin drum being provided with a plurality of pins and that of the pocket drum with a plurality of pockets, and synchronising means for synchronising the rotation of the drums, said pins and pockets being so positioned on the drums and the synchronising means being so arranged that each pin is in virtual mesh with a pocket as they pass through the plane joining the two axes.

The present invention also provides a method of pricking peas which comprises rotating a pin drum the curved surface of which has a plurality of pins and a pocket drum the curved surface of which has a plurality of pockets so that each pin is in virtual mesh with a pocket as they pass through the plane joining the axes of the two drums, placing peas in the pockets prior to their passage through the plane, pricking the peas with and impaling them on the pins during their passage through the plane, removing the peas impaled on the pins from the pockets by the movement of the pins relative to the pockets and then removing the peas from the pins.

It will be understood that though the cross-sectional area of the operative portion of the pin, that is the portion which enters the pulse to pierce it, can be varied over a range while still enabling the pulse to be pierced satisfactorily, that area must always be considerably smaller than the cross-sectional area of the pulse and hence of the pocket.

Preferably the pins are pointed. Preferably the pins are radial.

At least one of the drums may be conical or frustoconical but it is preferred that they are both cylindrical.

The synchronising means are preferably so arranged that when the drums rotate, corresponding sections rotate at substantially the same peripheral speed.

The term "meshing" has been used to indicate that the pin cooperates with a pocket, but without the pin engaging the side of the pocket. The pulse situated in a pocket may protrude above the curved surface of the pocket drum. Then, provided that the pin enters the pea, there is no need for it to penetrate so far that it also enters the pocket. The term "virtual meshing" has been used to indicate that the pin need not enter the pocket.

The axis of the pin drum may be situated at the same level as or above the axis of the pocket drum. In that case, the pulses are retained in their pockets by gravity

2

prior to being pricked. Alternatively, the curved surface of the pocket drum may move past and in contact with a curved stationary retaining plate, which retains the pulses in their pockets until after they have passed the pin drum.

5 The pin drum axis may in this case be situated below that of the pocket drum. The stationary plate must be provided with slots or apertures through which the pins can pass.

The means for feeding the pulses to the pockets preferably include a feed hopper, the sides of which terminate close to or make contact with the curved surface of the pocket drum. Assuming that the pocket drum is intended to be rotated in an anti-clockwise direction, the feed hopper should be situated in the 12 to 3 o'clock quarter.

10 The pin drum is preferably situated in the 9 to 12 o'clock quarter, the plane joining the centres of the axes of the two drums making an angle between 30—60° to the base of the machine and hence to the horizontal. Means 20 may be provided at the leading face of the hopper to prevent peas being carried over by the pocket drum unless they are situated in a pocket. These means may be constituted by the leading face extending to the curved surface of the pocket drum; in that case the leading face 25 should be made of resilient material. Preferably the lower portion of the leading face stops short of the curved surface of the pocket drum or is omitted and a rotatable brush is provided for sweeping the peas situated on top of the curved surface backwards towards the hopper.

30 Means are preferably provided for removing pulses which have become impaled during their passage through the plane. These removing means may be in the form of a slotted plate. Where a curved retaining plate is used, this may also constitute the removing means. Alternatively, means may be provided for retracting the pins into the pin drum so that the peas are forced off the pins by the curved surface of that drum.

35 Preferred examples of a pricking machine according to the present invention designed for pricking peas will now be described with reference to the accompanying drawings in which:

FIG. 1 shows a side elevation of the machine,
FIG. 2 shows a plan view of the machine shown in FIG. 1,

45 FIG. 3 shows diagrammatically an elevation of an alternative embodiment,

FIG. 4 shows diagrammatically a plan view of a detail of the embodiment shown in FIG. 3.

50 Referring to FIGS. 1 and 2, the frame of the machine comprises a base 1, vertical frame members 2, 3 and 4, horizontal frame members 5 and 6, two pairs of cross members 7 and 8. Cross member 7 makes an angle of 45° to the base.

55 The pocket drum 9 is secured to a shaft 10 which is rotatably mounted in bearings 11 fixed to cross member 7. A pulley 12 is secured to shaft 10 and a spur gear wheel 13 to a boss of drum 9. The curved surface of drum 9 is provided with a plurality of pockets 14 disposed in straight rows which are equispaced circumferentially around the pocket drum. The pockets in each row are equispaced from one another, any pocket of any one row lying on the same circle as one pocket of each of the other rows.

60 The pin drum 15 is rotatably mounted on a shaft 16 which is secured in supports 17 fixed to cross members 7. A spur gear wheel 18, which is in mesh with gear wheel 13 is secured to a boss of the drum 15. The

curved surface of drum 15 is provided with a plurality of pins 19 disposed in straight rows which are equispaced circumferentially around the pin drum. The pins in each row are equispaced circumferentially around the pin drum. The pins in each row are equispaced from one another, any pin of any one row lying on the same circle as one pin of each of the other rows. The peripheral distance between the centre lines of rows of pockets substantially equals that between rows of pins, and the distance between pockets in any row equals that between pins in any row. The pitch circle diameters of the gear wheels are such that the pins of any row mesh with the pockets of any row as those rows pass through the plane joining the axes of the drums.

The pins 19 project through holes in the curved surface of drum 15. Each row of pins is secured to a bar (not shown) which rotates with the curved surface. Each bar is provided with a follower which co-operates with a cam (not shown) secured to the stationary shaft to cause the bar to move radially towards and away from the curved surface. The arrangement is such that the cam pushes the follower and hence the bar outwards, thereby causing the pins to project through the curved surface of the pin drum. This is similar to an arrangement illustrated in U.S. Patents Nos. 457,744 and 494,105.

The machine is provided with a supply hopper 20 which is situated above a vibratory feeder 21. For the sake of clarity, supply hopper 20 has been omitted from FIG. 2. Vibratory feeder 21 feeds a feed hopper 22 having sides 23, 24 and 25, the lower edges of which almost make contact with the curved surface of the lower drum 9.

A cylindrical brush 26 is secured to a shaft 27 rotatably mounted in bearings 28 fixed to the horizontal frame members. A pulley 29 is also secured to the shaft 27.

The machine is powered by an electric motor 30 which drives a reduction gear box 31. The output shaft 32 of the reduction gear has pulleys 33 and 34 secured to it. Pulley 33 drives the pulley 12 by means of a belt 35. Pulley 34 drives a pulley 36 secured to a shaft 37 rotatably mounted in bearings 38 secured to the horizontal members. Also secured to shaft 37 is a further pulley 39 which drives pulley 29 by means of belt 40. For the sake of clarity, the belts have been omitted from FIG. 2.

In the particular embodiment described, the diameter of the pocket drum 9 was 21 $\frac{3}{4}$ "; the diameter of the pockets was $\frac{1}{2}$ " and their full diameter depth .225". There were 72 rows of pockets at 5° intervals, each row having 16 pockets at $\frac{1}{16}$ " pitch. The pitch circle diameter of gear wheel 13 was also 21 $\frac{3}{4}$ ". The curved surface of the pin drum 15 was constituted by a series of flat slats. The diameter of the pin drum was 14" across flats. The pitch circle diameter of gear wheel 18 was 14 $\frac{1}{2}$ ". The maximum projection of the pins was $\frac{1}{2}$ ". Their diameter was $\frac{3}{44}$ " and their exposed end was tapered to a point having an inclusive angle of 20°.

Thus the peripheral speed of the pocket drum equalled the peripheral speed of the pins measured at a point flush with the curved surface of the pocket drum. Thus the peripheral speed of the pin drum was very slightly less than that of the pocket drum but as the distance between the curved surfaces of the two drums was small compared with their radii, the peripheral speeds of the drums were substantially equal.

In operation, the supply hopper 20 supplies peas to the vibratory feeder 21 which feeds them to feed hopper 22. The vibratory feeder is adjusted to maintain the level of peas in feed hopper 22 constant. Drum 9 is rotated anti-clockwise and the pockets in its curved surface, which surface constitutes the floor of feed hopper 22, become filled with peas, one in each pocket. Any peas which—though not situated in a pocket—are carried upwards by the curved surface, are brushed back to-

wards the hopper by the brush 26 which is also rotated in an anti-clockwise direction.

As a row of pockets approaches the plane joining the two shafts, a row of pins which has previously been pushed outwards, enters the correspondingly approaching row of pockets and punctures the peas therein. The peas will remain impaled on the pins when the pins move out of engagement with the pockets. A chute 41 is situated below drum 15 to guide the peas to a container as they are forced off the pins when the latter are retracted.

It will be noted that any pea which has not become impaled on a pin (for example because the pea is of excessively soft texture or because it is undersized) will not be deposited into chute 41 but will fall out of the pocket as the pocket drum continues to rotate, into a tray (not shown) placed below the drum.

In the alternative embodiment shown in FIGS. 3 and 4, the pocket drum 42 is identical to pocket drum 9 shown in FIGS. 1 and 2. The pins 43 of pin drum 44 are, however, fixed relative to the curved surface of the pin drum instead of being movable radially. The pins 43 pass through a stationary slightly curved plate 45 having slots 46 before entering the pockets, and the peas subsequently impaled on the pins are removed therefrom when the pin passes out of the plate.

I claim:

1. A pricking machine comprising a pin drum and a pocket drum mounted for rotation about parallel axes, with their peripheries moving in close proximity to one another, a plurality of pins carried on said pin drum in a predetermined pattern along its periphery, a plurality of pockets in the periphery of said pocket drum arranged in a predetermined pattern, the pattern of said pins corresponding to the pattern of said pockets, with each pin entering a pocket in the portion of the peripheries in close proximity to one another and then withdrawing therefrom, means for depositing pulses individually in said pockets prior to the entry of said pins into said pocket, and drive means connected between said drums for synchronising the rotation of corresponding peripheral sections of the drum.

2. A pricking machine as claimed in claim 1, in which the drive means includes means for rotating corresponding sections of each drum at substantially the same peripheral speed.

3. A pricking machine as claimed in claim 1, in which the pins extend radially from the pin drum.

4. A pricking machine comprising a cylindrical pin drum and a cylindrical pocket drum mounted for rotation about parallel axes with their peripheries moving in close proximity to each other, a plurality of pins carried on said pin drum in a predetermined pattern along its periphery, a plurality of pockets in the periphery of said pocket drum arranged in a pattern corresponding to that of said pins, with the pins of the one drum successively entering and then leaving the pockets of the pocket drum where the drum peripheries are closest, means for depositing a pulse in each of said pockets where they become impaled on said pins that enter said pockets, and drive means connected between said drums for operating them at the same peripheral speeds.

5. A pricking machine for pricking pulses comprising a pin drum and a pocket drum mounted for rotation about parallel axes with their peripheries in close proximity to one another, a plurality of pins extending radially from the periphery of said pin drum, a plurality of pockets in the periphery of said pocket drum, drive means connected between said drums for synchronising the rotation of the drums, said pins and said pockets arranged in corresponding patterns on their respective drums with each pin entering and leaving a pocket as it passes through the plane containing the two axes, means for depositing a pulse in each of said pockets for piercing by a pin entering and then leaving that pocket, and means for removing pulses pierced by said pins.

6. A pricking machine as set forth in claim 5, in which the removing means comprises a slotted plate disposed between said drums with its slots aligned with the paths of movement of the pins, and through the slots of which the pins enter and then leave during rotation of said drums, the plate diverging from said pin drum as the pins leave said pockets and pushing pulses impaled on the pins from the pins after the pins leave the pockets.

7. A pricking machine as set forth in claim 5, in which the removing means comprises means for retracting the pins into the pin drum so that pulses impaled on the pins are forced off by contact with the curved surface of the pin drum.

8. A pricking machine comprising a cylindrical pin drum and a cylindrical pocket drum mounted for rotation about parallel axes, a plurality of pins disposed in a plurality of straight rows with the rows equally spaced in a pattern around the circumference of the pin drum, each pin of each row lying in the same plane transverse to the axis of the drum as the corresponding pins in the other rows, a plurality of pockets arranged about the surface of the pocket drum in a pattern corresponding to that of said pins with each pin entering and then leaving the pockets during rotation of said drums, means for depositing a pulse in each of said pockets for piercing by a pin that enters said pocket, and drive means interconnecting said drums for causing rotation of the drums at the same peripheral speeds.

9. A pricking machine as set forth in claim 8, in which the drive means includes means which rotate corresponding sections of the drums at substantially the same peripheral speed.

10. A pricking machine comprising a cylindrical pin drum and a cylindrical pocket drum mounted for rotation about parallel axes, a plurality of pins disposed radially on the peripheral surface of said pin drum in a plurality of straight rows with the rows equally spaced circumferentially around the pin drum, each pin of each row lying in the same plane transverse to the axes of the pin drum, a plurality of pockets in the periphery of said pocket drum disposed in a pattern corresponding to that of the pins, drive means interconnecting said drums for synchronizing the rotation of the drums at the same peripheral speed of the drums, with said pins entering and then leaving correspondingly disposed pockets as the drums rotate as the pins approach, pass through, and then leave a plane joining the axes of the drums, means for depositing a pulse in each of said pockets approaching said plane for piercing by a pin, and pulse removing means comprising a plate disposed between the peripheries of said drums and having a plurality of slots, the slots being aligned with and in the paths of movement of the pins with the plate diverging from the pin drum after the pins pass through said plane, whereby pulses impaled on the pins are removed by the plate during the passage of the pins through it.

11. A pricking machine comprising a cylindrical pin drum and a cylindrical pocket drum mounted for rotation about their respective axes, a plurality of pins mounted on said pin drum in a plurality of straight rows equally spaced circumferentially around the pin drum, the pins in each row being spaced equally from one another, any pin of any row lying on the same circle as one pin of each of the other rows, a plurality of pockets disposed on said pocket drum in a pattern similar to said pins, drive means connected to said drums so that the peripheral speeds of the drums are substantially equal, said pins and pockets being arranged in a corresponding pattern on their respective drums with each pin entering and leaving a pocket as it passes through the plane containing the two axes, means for depositing a pulse in each of said pockets for piercing by a pin entering and then leaving that pocket, and means for retracting the pins into

the pin drum so that pulses impaled on the pins are forced off by contact with the curved surface of the pin drum.

12. A pricking machine as claimed in claim 11 further comprising a feed hopper having sides that terminate close to the surface of the pocket drum, a discharge portion of said feed hopper positioned adjacent the surface of the pocket drum, and a rotatable brush mounted at the top of the pocket drum to sweep pulses toward the hopper.

13. A method of pricking peas which comprises the steps of conveying a plurality of peas along a predetermined path, progressively impaling the peas on pins during their travel in said path, and then progressively removing the impaled peas from said pins during their further travel along said path.

14. A method of pricking pulses comprising the steps of moving a plurality of pockets progressively along a selected path, placing pulses individually in said pockets at one location in said path, progressively pricking said pulses with pins at a later location in said path, and then removing the pulses from said pins at a still later location in said path.

15. A pricking machine for pricking pulses comprising a pin drum mounted for rotation about a first axis, a plurality of pins extending radially from the periphery of said pin drum in a predetermined pattern, a pocket drum mounted for rotation about a second axis, a plurality of pockets in the periphery of said pocket drum arranged

30 in a predetermined pattern, the pattern of said pins and the pattern of said pockets being arranged in corresponding patterns on their respective drums with each pin entering and leaving a pocket as it passes through said first and second axes, each of said pins having a substantially smaller cross-section than that of said pocket, means for depositing a pulse in each of said pockets for piercing by a pin entering and then leaving that pocket, and drive means connected between said drums for operating them at the peripheral speeds.

40 16. A pricking machine for pricking pulses comprising a pin drum and a pocket drum mounted for rotation about parallel axes with their peripheries moving in close proximity to each other, the axis of said pin drum being above a horizontal plane through the axis of said pocket drum,

45 a plurality of pins carried on said pin drum in a predetermined pattern along its periphery, a plurality of pockets in the periphery of said pocket drum arranged in a predetermined pattern, the pattern of said pins and the pattern of said pockets being arranged in corresponding patterns on their respective drums with each pin protruding into a pocket when in a plane passing through the axis of said drums, means for depositing a pulse in each of said pockets for piercing by a pin, drive means connected between said drums for synchronizing the

50 rotation of corresponding peripheral sections of the drums, the direction of rotation of contiguous sections of the drums being downwardly, and means for removing pulses that remain on said pins after piercing, the pulses remaining in pockets after piercing being removed by gravity at approximately the lowermost point of travel of the surface of said pocket drum.

17. A pricking machine for pricking pulses comprising a pin drum and a pocket drum mounted for rotation about parallel axes, a plurality of pins carried on said

65 pin drum in a predetermined pattern, a plurality of pockets in the periphery of said pocket drum arranged in a predetermined pattern, said plurality of pins being arranged in a pattern whereby a single pin is in alignment with a corresponding pocket at at least one portion of the rotational travel of said drums, drive means connected between said drums for synchronizing the peripheral speeds of said drums, means for depositing a pulse in each of said pockets for piercing by a pin entering and then leaving that pocket, and means for removing pulses that remain on said pins after being pierced by said pins, the

70 75

pulses remaining in said pockets after piercing being removed from said pockets by gravity.

UNITED STATES PATENT OFFICE
CERTIFICATE OF CORRECTION

Patent No. 3,028,893

April 10, 1962

John Edwin Cannell

It is hereby certified that error appears in the above numbered patent requiring correction and that the said Letters Patent should read as corrected below.

Column 6, line 52, for "axis" read -- axes --; line 54, for "synchronizing" read -- synchronizing --; line 66, for "pockets", second occurrence, read -- pocket --; column 8, line 1, for "949,105" read -- 494,105 --.

Signed and sealed this 14th day of August 1962.
